UNITED STATES PATENT OFFICE.

ELI McALLISTER, OF ALBIA, IOWA.

WATER-ELEVATOR.

SPECIFICATION forming part of Letters Patent No. 311,664, dated February 3, 1885.

Application filed March 29, 1884. (No model.)

To all whom it may concern:

Be it known that I, ELI McALLISTER, of Albia, in the county of Monroe and State of Iowa, have invented a new and Improved 5 Water-Elevator, of which the following is a full, clear, and exact description.

My invention relates to the class of water-elevators in which two buckets counterbalance each other and are operated alternately 10 by a windlass; and it consists in the combination, with one or more buckets, of a sprocket-wheel, belt-chain, and bail-chains connected with a wide link in the belt-chain, and with the upper portion of the bucket, the extremity of the said belt-chain being connected with the side of the bucket near the bottom, the belt-chain and bail-chains being arranged 15 relative to each other, so that when the extremity of the belt-chain is being drawn toward the sprocket-wheel the bail-chains will receive a slower motion by being drawn over the shaft of the sprocket-wheel. The effect 20 of this operation is to impart to the bucket a differential motion which will raise the bottom thereof faster than the top after it has passed the trough of the well-curb, so that the 25 water will be poured from the bucket into the trough.

Reference is to be had to the accompanying 30 drawings, forming part of this specification, in which similar letters of reference indicate corresponding parts in both the figures.

Figure 1 is a side sectional elevation of my 35 improved water-elevator, and Fig. 2 is a front elevation.

A frame, A, placed over the well, supports a horizontal shaft, B, upon which, in the center of the frame, is secured the sprocket-wheel C. The end of the shaft outside of the frame 40 A is provided with a crank, D, by which it is turned. A belt-chain, E, formed of square links adapted to the teeth of the sprocket-wheel C, is connected at each end with a bucket, F, near the bottom thereof, and upon the outer side. One of the links of the chain E near each end of the chain is provided with eyes a, projecting from opposite sides thereof, and bail-chains b connected with these eyes are attached to opposite sides of the bucket 45 F, near the top, in a line parallel with the shaft B. Across the top of each bucket is secured a curved guard, c, for preventing one bucket from catching upon the other or upon parts of the frame or sprocket-wheel.

Across the center of the frame A, directly 55 under the shaft B, and parallel with it, is placed a trough, G, which is connected with the spout H, extending outside of the frame A, in position to discharge the water elevated by the apparatus into a pail or other receptacle. By turning the shaft B one of the buckets F is raised, while the other is lowered, and after it has passed the trough G the bottom of the bucket is raised at the same rate of speed, 60 while the upper end of the bucket remains nearly stationary, being raised only through the distance due to the winding of the bail-chains b partly around the shaft B. This tips the bucket sufficiently to allow its contents to discharge into the trough G. By reversing 65 the motion of the shaft B the bucket just raised and tipped is first righted and then lowered, and when the other bucket nears the sprocket-wheel the operation just described is repeated. These oppositely-arranged buckets 70 balance each other, so that the power required to operate the elevator is simply that required to lift the water. The caps of the journal-boxes of the shaft B are connected by a curved yoke, d, which serves to strengthen 75 the frame A and to protect the sprocket-wheel C, and to prevent the buckets from being carried entirely over the sprocket-wheel.

Having thus described my invention, what I claim as new, and desire to secure by Letters 80 Patent, is—

1. The combination, with the bucket of a water-elevator, of a belt-chain attached to the sides thereof near the bottom, and bail-chains connected to the sides of the bucket and to 85 the belt-chains, substantially as described.

2. The combination, in a water-elevator, of a sprocket-wheel, C, buckets F, belt-chain E, attached to the sides of the buckets near the bottom, and bail-chains b, attached to opposite 90 sides of the buckets near the top, and connected with the eyes a, projecting from the belt-chain, as described.

3. The combination, with two oppositely-arranged buckets, F, belt-chain E, bail-chains 95 b, and sprocket-wheel C, for operating the same, of the centrally-arranged trough G, as described.

ELI McALLISTER.
